UNITED STATES PATENT OFFICE.

JOHN W. DENMEAD, OF AKRON, OHIO.

ATTACHING MEANS FOR RUBBER HEELS.

1,344,443.

Specification of Letters Patent. Patented June 22, 1920.

Application filed August 6, 1919. Serial No. 315,584.

To all whom it may concern:

Be it known that I, JOHN W. DENMEAD, a citizen of the United States, residing at Akron, in the county of Summit and State 5 of Ohio, have invented new and useful Improvements in Attaching Means for Rubber Heels, of which the following is a specification.

This invention relates to resilient heels 10 and has especial relation to a new and improved means for fastening rubber heels to shoes.

The object of the invention is to provide a new and novel means for connecting a 15 cushioning element to the heel portion of shoes whereby rubber heels may be quickly and easily attached to such shoes.

Ordinarily such heels are attached by 20 nails, screws or similar fastening means. This method not only reduces the resiliency of the heel, but as the rubber is worn away by use, the nails or screws soon become exposed. A further objection to the ordinary 25 method of attaching such heels is that when such heels are worn thin or otherwise impaired by use it is necessary to employ a skilled workman to replace same.

Another object of the invention is therefore to provide a fastening means for such 30 heels which will not interfere with the resiliency thereof and which will hold the heels securely and permanently in place but which can be quickly and easily removed and replaced by the ordinary wearer.

To these several ends my invention consists in the peculiar construction, combination and arrangement of parts shown in the accompanying drawings which form a 35 part hereof, it being understood that changes and variations may be resorted to which come within the scope of the claim hereunto appended.

In the drawings in which similar reference numerals indicate like parts:

Figure 1 is a perspective view of the heel 45 portion of a shoe with a resilient cushioning element attached by a fastening means embodying this invention.

Fig. 2 is a transverse sectional view of the 50 same taken approximately on line 2 in Fig. 3.

Fig. 3 is a perspective view of a fastening means embodying my invention having portions broken away to clearly illustrate the manner of construction.

Referring now to the drawings in detail, 55 numeral 1 denotes the main heel portion of

a shoe, the numeral 2 a flat plate having the same general outline as the heel portion 1. Numeral 3 indicates the side portion of said device which is integral with said flat 60 plate 2 and extends at right angles thereto around the border thereof. The numeral 4 denotes a narrow inwardly projecting strip-like portion integral with the side portion 3 and the plate 2 and projecting inwardly 65 from the edge of said side portion at approximately a right angle thereto. The flat plate 2, the side portion 3 and the inwardly projecting portion 4 are formed of one piece of metal, it being forced into the position 70 above described. The portion 4 projecting under the plate 2 and having a surface parallel to the surface of said plate 2 forms a relatively shallow channel 8 which extends entirely around said fastening means and is 75 adapted to engage and hold the upper base portion of said rubber heel 5. The plate 2 is further provided with openings 7 which are constructed therein for the purpose of making said device lighter in weight and said 80 plate is further provided with countersunk screw holes adapted to receive the heads of screws 6, by which means said plate 2 is fastened to the heel portion of said shoe 1.

In use, plate 2 is attached to the heel portion 1 by screws, nails or other convenient means; the said portion 3 forming a shallow cavity into which the cushion element is forced.

It will be noted that the elasticity of the 90 material will permit its being forced past the inwardly projecting member 4 whereupon it will expand and fill the channel 8. In this position the base of the resilient heel portion 5 will be in contact with the surface 95 of the plate 2 and will be held in a constant state of compression by the inwardly extending flange 4. It will be noted that the rubber heel 5 is securely held within the wall 3 by reason of the flange 4 compressing the 100 rubber at the point where it engages same, and the portion of the heel that lies above said flange 4 expanding into the channel 8. The rubber heel, it is noted, is formed with perfectly straight sides, that is, the upper 105 peripheral edge of the rubber heel is upon the same vertical plane as the lower peripheral edge. There is no required shaping of the rubber heel such as making one end larger than the other to hold it in its place, 110 as is ordinarily the case. Thus, when the tread face of the heel becomes worn, say

along one edge, the heel may be removed and inverted to expose the other face thereof as a wearing face. This is accomplished by simply compressing the heel to remove from the plate flange, and again compressing the inserted end of the heel to engage it with the flange and wall.

Having thus described my invention what I claim as new and desire to secure by Letters-Patent is:

10 Attaching means for rubber heels including a metallic plate having a depending wall extending substantially at right angles therefrom, an inwardly projecting flange carried by the lower end of said wall forming a

channel between the flange and plate, and a rubber heel substantially coextensive with the diameter of said plate and having the upper and lower edges of its periphery in the same vertical plane, said heel adapted 20 to be retained between the depending wall of said plate with the inwardly directed flange compressing the rubber at the point of engagement, the portion of the rubber heel above said flange expanding into the channel 25 between the flange and plate.

In testimony whereof I have hereunto set my hand.

JOHN W. DENMEAD.
